UNITED STATES PATENT OFFICE.

ALVIN THORNBRUGH, OF MANLY, IOWA, ASSIGNOR OF ONE-HALF TO CARL HENRY HASS, OF MANLY, IOWA.

LUBRICATING DEVICE.

Application filed May 6, 1925. Serial No. 28,481.

To all whom it may concern:

Be it known that I, ALVIN THORNBRUGH, a citizen of the United States, residing at Manly, in the county of Worth and State 5 of Iowa, have invented a new and useful Lubricating Device, of which the following is a specification.

This invention aims to provide novel means for the lubricating of all journals 19 under all classes of cars, locomotives, locomotive tenders and other vehicles, and to improve generally and to enhance the utility of devices of that kind to which the invention appertains.

15 Figure 1 shows in vertical section, a device constructed in accordance with the invention; Figure 2 is a cross section on the line 2—2 of Figure 1; Figure 3 is a horizontal section; Figure 4 is a plan of the bearing; Figure 5 is a plan of the pan.

The numeral 1 marks a casing, and the numeral 2 designates the axle of a freight car or any other vehicle, the axle extending into the casing and cooperating with a 25 bearing 3 held in place by any suitable securing means 4 known in the art. There is a guide 5 in the rear end of the casing 1, wherein operates a closure including a slide plate 6 carrying a packing strip 7 fitting 30 closely about the axle 2, the axle passing through the closure and through an opening 8 in the rear end of the casing 1, the packing strip 7 preventing dirt from entering the casing 1.

35 A trough-shaped pan 9 is located below the axle or rotatable member 2, the end walls of the pan being in the form of seats 10 for packings 11 which prevent a leakage of oil from the pan when the pan is thrust 40 upwardly by a compression spring 12 abutting against the bottom of the casing 1 and against the bottom of the pan 9, the spring being retained in place by bosses 14 on the pan and on the casing. The pan 9 has a 45 transverse oil pocket 15 into which dips a distributor ring 16 receiving the axle 2 and

running frictionally and loosely thereon, responsive to the rotation of the part 2. The bearing 3 has a transverse recess 17 for the reception of the upper part of the 50 ring. The concave surface 18 of the bearing 3 (wherein a portion of the axle 2 is received rotatably) has diverging oil grooves 19 and 20 located on opposite sides of the recess 17 and communicating therewith, the 55 recess 17 intersecting the concave surface 18 of the bearing, as Figures 4 and 1 clearly show.

The ring 16, being rotated responsive to the rotation of the axle 2, carries up the oil 60 from the pocket 15 and distributes it on the axle 2 within the recess 17, the oil flowing along the grooves 19 and 20 of the bearing and being distributed to the concaved surface 18 of the bearing, and through the 65 contacting upper portion of the axle 2.

The device shown and described will effect lubrication with decreased cost of oil and will also lengthen the life of parts subjected to wear, hot boxes and like annoyances 70 being avoided. A mechanic can make changes in the form shown, without departing from the spirit of the invention.

I claim:

In a device of the class described, a casing, a bearing in the upper portion of the casing and provided with a concaved surface intersected by a transverse recess, a rotatable member journaled on said surface, a trough-shaped pan in the lower portion of the casing and having a transverse oil pocket, a compression spring cooperating with the pan and the casing to hold the pan in operative relation to the rotatable member, and a distributor ring running loosely on the rotatable member and extended into the 75 pocket and into the recess.

In testimony that I claim the foregoing as my own, I have hereto affixed my signature.

ALVIN THORNBRUGH.
